UNITED STATES PATENT OFFICE.

JACOB T. JOHNSON, OF ATLANTA, GEORGIA.

LIGHT-FIXTURE.

1,185,330.

Specification of Letters Patent.

Patented May 30, 1916.

Application filed January 29, 1915. Serial No. 5,069.

To all whom it may concern:

Be it known that I, JACOB T. JOHNSON, a citizen of the United States, residing at Atlanta, in the county of Fulton and State 5 of Georgia, have invented a new and useful Light-Fixture, of which the following is a specification.

The present invention appertains to fixtures for incandescent electric lamps or for 10 other lights, and aims to provide a light fixture embodying a shade and holder therefor, the said parts having novel interengageable portions or means whereby the shade may be readily applied to and detached from the 15 holder.

Another object of the invention is the provision of a light fixture embodying the shade and holder, each of which has integral means, whereby said means are coöperable 20 for readily applying the shade to and removing the same from the holder, and in order that set screws, clasps and similar independent securing elements need not be employed. This provides a notable feature 25 of the invention, in that, the shade and holder each embody but one part which reduces the complete fixture to but two parts, each of which is comparatively simple, substantial and inexpensive in construction.

It is also within the scope of the invention, to provide a fixture of that nature, which enables the shade to be conveniently applied to and removed from the holder, which enables the fixtures in bulk or quantities 35 to be compactly stored or boxed, and which renders the fixture serviceable, practical and efficient in use.

With the foregoing and other objects in view which will appear as the description 40 proceeds, the invention resides in the combination and arrangement of parts and in the details of construction hereinafter described and claimed, it being understood that changes in the precise embodiment of the invention herein disclosed can be made within 45 the scope of what is claimed, without departing from the spirit of the invention.

The invention is illustrated in the accompanying drawings, wherein:—

50 Figure 1 is a perspective view illustrating the holder and shade separated, a portion of the shade being broken away. Fig. 2 is a sectional view of a fixture illustrating the interengaging portions of the shade and holder reversed. Fig. 3 is a perspective detail illustrating a modification.

In Fig. 1, there is illustrated a holder 83 and shade 84. The holder 83 embodies an annular gallery or ring 85 having the upper spider 86 for attaching it to a lamp or other support, and the lower edge of the gallery 85 is provided with inturned tongues 87 which are coiled and corrugated. The shade 84 is provided with an outturned annular flange 88 to enter the gallery 85, and the flange 88 is provided with recesses 89 for the passage of the tongues 87, the lower face of the flange 88 being corrugated, as at 90, so that the corrugations of the tongues 87 and flange 88 are adapted to hold the shade against relative rotation with respect to the holder when the shade is applied to the holder in the manner above indicated.

Fig. 2 illustrates a reversal of the fixture 75 illustrated in Fig. 1, in that the interengaging portions of the holder 91 and shade 92 are reversed. The holder 91 embodies the gallery 93 having the spider 94, and the lower tongues 95 which are bent outwardly are coiled and corrugated, the same as the 80 tongues 87. The flange 96 of the shade 92 is turned inwardly, and is provided with recesses 97 for the passage of the tongues 95, and the lower face of the flange 96 is corrugated, as at 98, to engage the corruga- 85 tions of the tongues 95.

Fig. 3 illustrates the holder 61 provided with a corrugated ear 62 that is not curled or bent back. This ear can be used either upon the exterior or interior of the holder, 90 and is engageable with the corrugated flange of the shade the same as the corrugated portions of the holder above described.

The interengageable corrugated portions 95 of the shade and holder are of advantage since the shade can be held at various angular positions relative to the holder, and when the shade is applied and turned relative to the holder, the corrugations of the two parts in moving over one another will 100 cause the shade to vibrate and produce a series of clicks. This will enable the operator to conveniently and effectively apply the shade to the holder, even in darkness, since the movement of the corrugations over one another will be perceptible to the sense 105 of touch, and will inform the operator that the shade is being properly applied to the holder.

From the foregoing, taken in connection 110 with the drawings, it is thought that the advantages and capabilities of the present in-

vention will be apparent to those versed in the art, it being noted that the several forms of the invention have common and independent advantages due to the general 5 and specific details of construction.

Having thus described the invention, what is claimed as new is:

1. A light fixture comprising a shade and holder therefor, one part having a flange 10 provided with recesses, the other part having portions to pass through the recesses and bear against the flange, and the flange having corrugations between a pair of the recesses, one of said portions also having 15 corrugations with which the corrugations of the flange are coöperable to limit the relative rotation of the parts.
2. A light fixture comprising a shade and holder therefor, the shade having a corrugated flange provided with recesses, and the holder having corrugated portions to pass 20 through the said recesses and for holding said flange.
3. A shade having a flange provided with 25 recesses, the flange having a series of corrugations between a pair of the recesses to co-operate with a corrugated portion of a holder.

4. A shade holder having corrugated portions for the engagement of the corrugated 30 flange of a shade.

5. A shade holder having coiled and corrugated tongues for the engagement of the flange of a shade.

6. A light fixture comprising a shade and 35 holder therefor, the shade having a flange provided with recesses and corrugations, and the holder having coiled and corrugated tongues to pass through the said recesses and to support the flange, the corrugations 40 of said tongues and flange being interengageable.

In testimony that I claim the foregoing as my own, I have hereto affixed my signature in the presence of two witnesses.

JACOB T. JOHNSON.
